Primary Examiner—Mitchell Siegel

(**) Term: **14 Years**

(57) **CLAIM**

(21) Appl. No.: **29/115,694**

The ornamental design for a pressurized oil mist receiving device, as shown and described.

(22) Filed: **Dec. 20, 1999**

DESCRIPTION

(51) LOC (7) Cl. **23-99**

FIG. 1 is a perspective view of a pressurized oil mist receiving device showing my new design;

(52) U.S. Cl. **D23/416**

FIG. 2 is a front elevational view thereof;

(58) Field of Search D23/416, 213;

FIG. 3 is a rear elevational view thereof;

210/23, 484, 494; 55/74, 98, 186, 487;

FIG. 4 is a top plan view thereof;

417/203

FIG. 5 is a bottom plan view thereof;

(56) **References Cited**

FIG. 6 is a left side elevational view thereof; and,

U.S. PATENT DOCUMENTS

FIG. 7 is a right side elevational view thereof.
